UNITED STATES PATENT OFFICE.

FRANK K. AMREIHN, OF DETROIT, MICHIGAN, ASSIGNOR TO THE STRATFORD PHONOGRAPH COMPANY, OF ASHLAND, OHIO, A CORPORATION OF OHIO.

DESIGN FOR A PHONOGRAPH-HORN.

56,644.

Specification for Design.

Patented Nov. 23, 1920.

Application filed February 10, 1920. Serial No. 357,683. Term of patent 3½ years.

To all whom it may concern:

Be it known that I, FRANK K. AMREIHN, a citizen of the United States, residing at the city of Detroit, county of Wayne, State of Michigan, have invented a new, original, and ornamental Design for a Phonograph-Horn, of which the following is a specification, reference being had to the accompanying drawing, forming part thereof.

Figure 1 is a plan view of a phonograph horn, showing my new design.

Fig. 2 is a side elevation thereof, and
Fig. 3 is a front elevation thereof.

I claim:

The ornamental design for a phonograph horn as shown.

FRANK K. AMREIHN.
